223,211

THERMOMETER OR SIMILAR ARTICLE

Clayton A. Laughlin, Minneapolis, Minn., assignor to
Arthur Salm Inc., Chicago, Ill.

Filed June 1, 1970, Ser. No. 23,235

Term of patent 14 years

Int. Cl. D10—03

U.S. Cl. D52—7

FIG. 2.

FIG. 3.

FIG. 1.

FIG. 4.

FIG. 5.

FIG. 1 is a perspective view of a thermometer or similar article showing my new design;

FIG. 2 is a front elevation view of FIG. 1;

FIG. 3 is a top plan view thereof;

FIG. 4 is a right side elevation view of FIG. 2, the opposite side being a mirror image thereof; and

FIG. 5 is a rear elevational view of FIG. 2.

The bottom portions not shown are plain and unornamented.

I claim:

The ornamental design for a thermometer or similar article, substantially as shown and described.
